F. Barton Brown.
By Crosby Gregory, Atty.

UNITED STATES PATENT OFFICE.

F. BARTON BROWN, OF BOSTON, MASSACHUSETTS, ASSIGNOR OF ONE-HALF
TO GEORGE FROST & CO., OF SAME PLACE.

CLASP.

SPECIFICATION forming part of Letters Patent No. 284,943, dated September 11, 1883.

Application filed July 30, 1883. (No model.)

To all whom it may concern:

Be it known that I, F. BARTON BROWN, of Boston, county of Suffolk, State of Massachusetts, have invented an Improvement in Clasps, 5 of which the following description, in connection with the accompanying drawings, is a specification, like letters on the drawings representing like parts.

This invention is an improvement upon the 10 clasp described in United States Patent No. 202,924, granted to me April 30, 1878, to which reference may be had, the said clasp being especially intended for use in connection with garment-supporters. In the clasp represented 15 in the said patent the rear end of the pivoted jaw, which is acted on and pressed inward by the wearer of the clasp to open it, normally stands so far out from the rigid or base jaw of the clasp as to leave a space between the rear 20 end of the pivoted jaw and the base-jaw, into which the clothing enters and becomes caught. To obviate this difficulty I have bent inwardly the rear end of the pivoted jaw of the clasp, and have provided the stationary jaw of the 25 clasp with an opening, into which the said bent rear end may enter when the clasp is opened, and at the rear end of the stationary jaw of the clasp I have bent a portion thereof upward from its back side, to form tubes or eyes for the 30 reception of the cords to which the clasp is attached, and the said tubes or eyes are so located and shaped as to project beyond the extremity of the rear end of the pivoted jaw when the same is closed by the action of the 35 spring of the clasp, thus effectually shielding the rear end of the pivoted jaw and preventing the catching of anything thereunder. The stationary jaw and the tubes or eyes which act as a fender for the rear end of the pivoted jaw 40 are made from a blank cut as a single piece from sheet metal.

My invention consists, essentially, in a clasp having a rigid or base jaw provided with cord-receiving tubes or eyes, to act also as a 45 fender, combined with a pivoted jaw, the rear end of which is bent inward, as will be described.

Figure 1 represents a blank suitable for the

manufacture of the stationary jaw of the clasp. Fig. 2 is a top or plan view of one of my improved clasps; Fig. 3, a longitudinal section thereof on the dotted line *x x*; and Fig. 4 is a cross-section of Fig. 3 on the line *y y*, looking in the direction of the arrow, Fig. 3.

The blank shown in Fig. 1, from which the rigid or base jaw *e* is made, has teeth *a* and projections *a'*, with holes *2* for the reception of the pin *b*, a hole or opening, *a²*, for the reception of the inwardly-turned rear end, *c²*, of the jaw *d*, pivoted on the pin *b*, and arms *a³*, which are adapted to be bent over to form tubes or eyes *c*, for the reception of the usual cords of a stocking or sleeve supporter. The blank shown in Fig. 1 is weakened in a measure by cutting from it the material to form the opening *a²*, for the reception of the rear end of the jaw *d*, and to compensate for this the blank is made wider than in the said patent between the projections *a'*, which are to be turned up to form ears for the pin *b* and the tubes or eyes *c*, so that when the eyes are formed and the ears turned up the widened shank of the blank will be turned up or over, as shown at *f*. The flanged part of the rigid or base jaw, by being turned upward, as described, adds very materially to the strength and durability of the said jaw. As shown in Fig. 3, it will be seen that the tubes or eyes *c* act as a fender for the rear end of the pivoted jaw *d*, so that clothing, &c., cannot get under the said rear end and between it and the rigid or base jaw. The spring *h* is as common to the 50 said patent.

I claim—

1. In a clasp, the rigid or base jaw provided with the cord-receiving tubes *c*, combined with the pivoted movable jaw, having its rear end bent inward, as described, to be shielded by the cord-receiving tubes when the clasp is closed, substantially as described.

2. The rigid or base jaw provided with an opening back of its ears, combined with the pivoted jaw, having its rear end bent inward toward the said rigid or base jaw, and adapted to enter the said opening when the clasp is 55 opened, substantially as described.

3. In a clasp, the pivoted jaw, combined with the rigid or base jaw provided with cord-receiving tubes or eyes and ears, and strengthened in its shank between the said ears and
5 eyes by turning up or over the edges of the metal forming the rigid or base jaw, substantially as described.

In testimony whereof I have signed my name to this specification in the presence of two subscribing witnesses.

F. BARTON BROWN.
